UNITED STATES PATENT OFFICE.

HARRY G. KELLY, OF OMAHA, NEBRASKA.

METHOD OF PREPARING ROOFING SHEETS.

Application filed July 2, 1924. Serial No. 723,821.

This invention relates to a method of preparing roofing sheets by stamping, perforating, mutilating or incising them to provide strips having ornamental borders; and in order that the borders may be formed and that the sheets may be thereafter rolled into a compact package for shipping, and that the sheets may be separated readily into strips after they have been delivered and unrolled, and that the borders will not become injured or changed in outline while being separated, said sheets are incised only sufficient to provide a part of each border, and the parts between the incisions or apertures are perforated or otherwise mechanically weakened along the line, angle or curve that will complete the form of the edge or border desired.

The borders of these strips, when applied to roofs, will usually present the appearance of either standard or ornamental shingles, but may be of any desired ornamental pattern, their outline or contour being perfect.

It is understood that roofing sheets have heretofore been incised to provide ornamental borders, and have been shipped or delivered in rolls, the incisions leaving uncut portions therebetween, the objectionable feature of such constructions being that the uncut portions must be of sufficient lengths or proportions, that the sheet, during the rough usage incident to shipping, will not become separated into strips, and that after delivery and when separated into strips, the outline for the borders will be imperfect, because there is no assurance of accurate separation on the exact line desired, through the uncut portion.

By use of the herein described method the sheets will not become separated into strips during shipment, and while being torn apart or separated along the weakened lines, angles, or curves, ready for use as strips, the design, pattern, outline or contour of the ornamental borders will be of the exact form desired.

The invention consists of the novel and useful disposition, arrangement and combination of incisions, punches, perforations, apertures and mutilations in roofing sheets, and the mechanical weakening of said sheets between such incisions or apertures as described herein and claimed, and as illustrated in the accompanying drawing, it being understood that changes in form, size, proportion, arrangement of mutilations and

minor details may be made, as found to be of advantage, said changes being determined by the scope of the invention as claimed.

In the drawing Fig. 1 is a plan view of a roll and part of an incised but undivided roofing sheet illustrating one embodiment of the invention. Fig. 2 is a plan view showing a part of a roof and an arrangement of strips having the appearance of ornamental shingles, said strips being parts of the roofing sheet shown in Fig. 1. Fig. 3 is a sectional view showing means for incising, perforating or mutilating a roofing sheet.

It should be stated that for roofing sheets which have gone into extensive use, various kinds of material, singly and combined, have been employed in their manufacture, said sheets being fibrous, flexible, strong and of a quality impervious to moisture, and for the purpose of being shipped they have generally been rolled into compact form; and in the practice of the present invention any of the roofing sheets mentioned may be used and may be prepared, as will now be described.

In the drawing I have shown a roll of roofing, indicated at 5, consisting of a sheet having any suitable length and width. In Fig. 1 the roofing sheet consists of longitudinal sections indicated at A, B and C, respectively. The sections A and C have rectilinear edges respectively indicated at d and e. At f are indicated numerous incisions, disposed in alignment, adjacent to each other, providing parts x intermediate the ends of the incisions, said parts x being perforated as indicated at v, said incisions and perforated parts being provided throughout the entire length of the sheet. Numerals 7 indicate triangular apertures which open on the incisions f, and at 8 are indicated slots which are disposed at right-angles to the incisions f and the line of perforations v and which open on the apertures 7, and it will be understood that after the package 5 has been unrolled, the section A may be separated from the section B, the perforations v permitting this separation since the sheet may be torn in line with the incisions, the convergent walls of two adjacent apertures 7 providing two opposed, convergent walls g of a strip 9 shown in Fig. 2.

It will be understood that, after a section A has been separated from the sheet shown in Fig. 1, the incisions f and the parts there-

between, torn on the line of the perforations *v*, will provide an edge which is approximately rectilinear for the section B, and midway between said edge and the edge *e* are numerous apertures 10 of rectangular form, and opening on said apertures are numerous incisions *h* which are disposed in alignment longitudinally of the sheet, portions 11 being provided, with perforations *v*, between the ends of said incisions, said perforations performing the same function as the perforations between the ends of incisions *f* first mentioned. Numerals 12 indicate opposed slots, these being disposed at right-angles to the incisions *h* and opening upon the apertures 10; and as described, two adjacent apertures 10 provide convergent walls *k* for the section B which provide two, opposed, convergent walls *m* for the strip 13 shown in Fig. 2. Also any two adjacent apertures 10 provide convergent walls *n* for the section C which also provide two, opposed, convergent walls *p* for the strip 14 shown in Fig. 2, the sections B and C being manually separated, the portions 11 being torn on the line of its perforations *v* for this purpose.

While I have shown perforations *v* in order that the sections A, B and C may be torn in a desired direction and on a desired line and to avoid an irregular and imperfect appearance, I may mutilate, score, stamp or otherwise weaken the fabric, but perforations are preferred.

It is obvious that a great variety in shapes of apertures as well as incisions may be employed for the sheets, so that ornamental borders will be formed for the strips, and I do not wish to be understood as limiting myself to any kind of ornamentation, the important feature of the invention being that the parts between the ends of the incisions will be weakened by perforations or equivalent means which will permit the sheets to be rolled and shipped without accidental separation and will prevent defacement or injury to the contour of the ornamental borders when the sheet is torn apart or separated into strips.

Any suitable means may be provided for incising, perforating or mutilating the sheets as above mentioned, and for this purpose I have shown a pair of co-acting rollers 18 and 19, adapted to be actuated by any suitable means, the roller 18 being provided with blades or projections *s* engaging in grooves *u* of roller 19 to form at intervals any desired incisions, perforations, apertures or mutilations in said roofing sheets, required for the formation of strips with ornamental borders, also recesses *t* therebetween provided with perforating or mutilating projections *y* to mechanically weaken the holder members *x* and 11, so that they may be manually torn in the exact line, angle, or curve to complete the form or contour of the strip desired.

While I have shown and described apertures, perforations and incisions in roofing sheets I do not wish to limit myself specifically to these features, and stamping, punching or otherwise mutilating said sheets may be practiced as substitutes for actual incisions, perforations and apertures, the holder-elements *x* and 11, of course, being employed and having such proportions as may be required for maintaining the sheets in connected condition, so that the product after being prepared may be shipped as rolls, without injury to the ornamental parts, and that a specific and approximately perfect outline of the ornamental borders will be maintained when the sheet is separated into strips. In some instances strips or sections of greater width are required than in others, and it is considered to be within the scope of the invention to form, longitudinally, of a sheet, a single line of incisions *h*, perforations *v* and apertures 10, whereby a sheet of standard width will provide two sections having equal width and area, and ornamentation of similar appearance.

The use of the invention will be appreciated since ornamentation may be readily effected by machinery and will effect a considerable saving in labor. Also the rolls may have the same form and appearance and may be shipped at the same expense as plain rolls of sheet roofing, and, as is obvious, the ornamental parts will be protected from injury while being shipped, this being a feature of great advantage.

I claim as my invention,

1. The herein described method of preparing sheets to be rolled into packages and when unrolled to be separated into strips having ornamental borders, which consists in forming two lines of perforations in said sheet approximately equi-distant from its longitudinal edges to provide three sections approximately of equal width, incising the sheet to form apertures providing uniform areas in two of the sections at opposed parts of a perforated line, and incising said sheet to form apertures providing uniform areas in the remaining section at one side of the remaining perforated line, said last named apertures having the form of the apertures in the two sections first named.

2. The herein described method of preparing sheets to be rolled into packages and when unrolled to be separated into strips having ornamental borders, which consists in incising the sheet to provide lines of apertures at uniform intervals longitudinally of the sheet, said apertures for each line being connected by incisions and perforations to provide a plurality of sections of approximately equal width and area.

In testimony whereof, I have affixed my signature.

HARRY G. KELLY.
